JOHN P. WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

METHOD OF MANUFACTURING UNION-SUITS AND DRAWERS.

1,342,010.

Specification of Letters Patent.

Patented June 1, 1920.

Application filed January 3, 1919, Serial No. 269,479. Renewed December 24, 1919. Serial No. 347,193.

To all whom it may concern:

Be it known that I, JOHN PETER WEIS, a citizen of the United States, residing at Nyack, in the county of Rockland and State 5 of New York, have invented certain new and useful Improvements in Methods of Manufacturing Union-Suits and Drawers, of which the following is a specification.

This invention relates to a method of 10 manufacture from flattened tubular goods of either union suits or drawers in which the legs and the body-covering portion are integral; the object of the invention being economy of labor and material.

15 In the accompanying drawing forming a part hereof and illustrating the product of a method, 1 is a piece of flattened tubular goods the back wall of which is indicated by *b*; 2 indicates armhole slits in the edges 20 of the flattened tube; 3 neck-opening cut-outs; 4 lengthwise slits over the chest and abdomen, in the front wall only of the flattened tube; 5 one of the two superimposed crotch-pieces cut out from between four legs 25 the ankle ends of which are contiguous; 5^a the end tongues of the two superimposed crotch-pieces; 6 notches for use in inserting gussets; and 7 the inside leg seaming. There 30 are two opposed notches 6 near the adjacent end portion of each two superimposed crotch-piece tongues, in practice about eight inches. Between the notches 6 of one garment and the corresponding notches 6 of the next successive garment, the inside leg 35 forming seams are formed; the edges of the leg-forming portions adjacent the tongues not being stitched.

The flattened tube is fed endwise in the direction of the arrow adjacent the drawing, and subsequently to the formation of 40 the two transversely opposed armholes 2 of the garment initially formed from the advancing end portion of the tube, the flattened tube as it travels forward is ultimately 45 slit at its two opposite edges to form on each edge an elongated slit at 2, each of these slits as shown at the left-hand end of the drawing being long enough to form in each edge of the flattened tube two contiguous 50 armholes of two garment-forming sections of the traveling tube. The neck cut-outs 3 are not made during the cutting operations now described, but are made during the subsequent finishing operations.

By the present method the chest-opening 55 slit 4 for women's union suit bodies, or for shirts ordinarily extends from *x* to about *x'*; but for men's garments such chest and front opening extends from *x* to *x''* forming a front opening from the neck down the 60 chest and abdomen. When this slit 4 which is midway between the side edges of the flattened tube and lengthwise of it, reaches its inward or lower end at *x''*, the lengthwise-cutting operation then comprises two cutting movements spaced apart and parallel 65 one to another as at *x''* to form the side edges of the initially superimposed crotch-piece tongues 5^a. The cutting operations each along the two parallel laterally-spaced 70 apart lines *x''* terminate at *x''* where they first diverge and then gradually converge to form two opposedly concave cuts through both walls of the flattened tube as from *x''* to *x''*. The centrally formed tongues 5^a are 75 transversely severed at their outer ends from the tube walls; thus two superimposed crotch-pieces are progressively formed, being released from the flattened tube and falling out from between the four leg-forming 80 portions 1^a produced at each side of the superimposed crotch-pieces. The two lines of seaming 7 constitute the inside seaming of these leg portions 1^a which are as yet integral at their ankle ends, and this seaming 85 is performed at the same time the concave cuts are made. When the two cuts from *x''* to *x''* reach the points *x''*, the two independent parallel cutting operations are again 90 performed from *x''* to *x''* to form the left-hand superimposed crotch-piece tongues 5^a continuing from *x''* to *x''*, and when these rear end tongues 5^a have been produced to the required extent the tongue ends are transversely cut off so that both crotch-pieces are 95 removed from the path of travel of the flattened tubes. As the tube continues in its travel a single cutting operation is again performed through the front wall of the flattened tube forming another abdominal and chest front 100 opening along the line 4^a, the cut extending for men's garments from *x''* to *x''* at the next following neck cut-out 3^a; or if women's garments as ordinarily required are to be made this last line of cut from *x''* will be 105 intermittent until the second intermediate point *x''* is reached where it will begin and continue to *x''*.

The successive notching at 6 is done progressively as the flattened tube travels in the direction of the arrow.

The cross line $z-z$ indicates the position 5 of a transverse cutting mechanism which is in a fixed position. The transverse line $y-y$ indicates the line of transverse cut for severing each two adjacent ankle ends without transversely severing the two crotch-pieces, 10 but this transverse severing along the line $y-y$ does not occur until that line of cut has come into the position of the transverse length-cutters at $z-z$. The line $x-x$ represents the line of transverse cutting 15 across the full width of the flattened tube to sever two adjacent shoulder ends of successive union suits or shirts formed from the tube and to provide contiguous to the line of cut at each edge of the flattened tube the 20 requisite pair of armholes for each garment. The drawing shows a section of tube long enough to form two successive union suits and a portion of the armholed end of the next succeeding union suit; but it will be 25 obvious that if in the progress of this tube cut and sewn at the inside of the leg-forming portions as described, the tube is successively cut in two crosswise on a line of cut coincident approximately with the two points 30 x' and x'' , successive pairs of drawers only would be formed. The approximate lines of cut for this transverse division of a union-suit-forming section of the flattened tube into pairs of drawers are indicated by 35 $w-w$. The cutting and sewing operations described as a part of this method may be performed in a properly organized machine with very great rapidity,—in practice at a speed of approximately 3,000 to 4,000 yards 40 per eight hours, and the method is useful in the production of all sizes including length size of union suits and drawers, from infants' sizes to the largest sizes required. The lengthwise slits may be through the front 45 or both walls of the flattened tube. Thus in sleeping garments for children, instead of the front slit in the front wall the slit is in the back wall of the flattened tube. It is not desirable by the present method to transversely cut in two along the lines $w-w$ the 50 successive union suits for the purpose of converting each into a pair of drawers and also a shirt, because it is practically required that the tail end of shirts shall overlap 55 the waist portion of drawers; and so when drawers only are to be made by this process, the body portion is shortened. In other words the transverse cut-off at $z-z$ is effected when the flattened tube portions indicated at $w-w$ reach the fixed position 60 of the transverse cutters at $z-z$. In small children's sizes of drawers, side slits 2 which form armholes in the union suits, are made at 2^a and become side slits of drop seat 65 drawers. The openings left between the

back and front walls of the tube from the opposed notches 6 to the free ends of the crotch-piece tongues, afford free edges to which the edges of crotch gussets etc. are stitched in the finishing operations.

70

What I claim is,—

1. The herein-described process of cutting and partially seaming successive leg garments from flattened tubular goods, consisting in successively cutting and partially 75 seaming from the flattened tube a succession of successive legged garments by progressively making through both walls of the flattened tube inwardly of the tube edges, two parallel cuts spaced apart, thereby 80 forming crotch-piece tongues; in continuing such cuts in the lengthwise direction of the flattened tube in opposed concave paths terminating in two parallel cuts spaced apart, thereby forming crotch-piece continuations 85 of the initially-formed tongues together with terminal crotch-piece tongues; in transversely severing the superposed crotch-piece tongues thus formed from the flattened tube; in opposingly notching, adjacent each pair of superposed crotch-piece tongues, the opposed superposed edges of 90 leg-forming portions left by removal of the crotch-pieces and their tongues; in seaming lengthwise of each concave cut from the first-formed to the last-formed notches; leaving the straight cut edges and the intermediate concave cut edges of the flattened tube unseamed from each notch to the transverse 95 end cut of the tongues unseamed; in transversely severing the flattened tube midway between the opposed notches at each end of the crotch-piece and tongue cut-out to form a pair of garments each having a pair of legs; and in lengthwise slitting the flattened tube.

100

2. The herein-described process of cutting and partially seaming successive leg garments from flattened tubular goods, consisting in successively cutting and partially 110 seaming from the flattened tube a succession of successive legged garments by progressively making through both walls of the flattened tube inwardly of the tube edges, two parallel cuts spaced apart, thereby forming 115 crotch-piece tongues; in continuing such cuts in the lengthwise direction of the flattened tube in opposed concave paths terminating in two parallel cuts spaced apart, thereby forming crotch-piece continuations 120 of the initially-formed tongues together with terminal crotch-piece tongues; in transversely severing the superposed crotch-piece tongues thus formed from the flattened tube; in opposingly notching, adjacent each 125 pair of superposed crotch-piece tongues, the opposed superposed edges of leg-forming portions left by removal of the crotch-pieces and their tongues; in seaming lengthwise of each concave cut from the first-formed to 130

the last-formed notches; leaving the straight cut edges and the intermediate concave cut edges of the flattened tube unseamed from each notch to the transverse end cut of the 5 tongues unseamed; in transversely severing the flattened tube midway between the opposed notches at each end of the crotch-piece and tongue cut-out to form a pair

of garments each having a pair of legs; in lengthwise slitting the flattened tube; and 10 in progressively and oppositely edge-slitting the flattened tube where required.

In testimony whereof I have hereunto set my hand this 31 day of December, 1918.

JOHN P. WEIS.
